UNITED STATES PATENT OFFICE.

GUSTAV B. PETSCHÉ, OF YONKERS, NEW YORK.

ROTARY COMPRESSOR.

1,380,018.

Specification of Letters Patent.

Patented May 31, 1921.

Application filed October 6, 1920. Serial No. 415,147.

To all whom it may concern:

Be it known that I, GUSTAV B. PETSCHÉ, a citizen of the United States of America, and resident of Yonkers, in the county of 5 Westchester, in the State of New York, have invented a certain new and useful Improvement in Rotary Compressors, of which the following is a true and exact description, reference being had to the accompanying 10 drawings, which form a part thereof.

My invention relates to compressors in which the compressing piston moves with high speed and with a great number of compressing strokes per minute. More particularly though not exclusively my invention is adapted for use with rotary compressors. The object of my invention is to dispense with delivery valves in such engines while at the same time retaining a 20 high rate of efficiency in compressors of this kind. In general practice a considerable amount of liquid is passed through these compressors together with the gas being compressed. This is generally oil or glycerin though some times, as in the case of condenser pumps, the liquid may consist of water. My invention consists, generally speaking, in so constructing the receiver of the compressor and the delivery ports leading into this receiver that the delivery ports 25 will be sealed with the liquid during the intervals between the discharge of gas through the delivery port into the receiver and I accomplish this by providing in the receiving chamber a liquid retaining chamber which should be of such capacity as to contain, above the delivery ports, a body of liquid of greater amount than will flow through the ports in a reversed direction 30 during the periods when the pressure on the compressor side of the ports is less than that in the receiver. In connection with such a receptacle I give the delivery ports leading into it such form and proportion 35 that while they will pass the compressed gas into the receiver at high speed they will offer considerable resistance to the backward flow of liquid.

My invention will be best understood as 40 described in connection with the drawings in which it is illustrated and in which—

Figure 1 is a side elevation of a rotary compressor provided with my improvement and taken on the section lines 1—1 of Fig. 2.

Fig. 2 is a front elevation taken partly on the section line 2—2 of Fig. 1.

Fig. 3 is a detail.

Fig. 4 is an enlarged detail view of a device for properly forming a delivery port so that it will pass the gas freely to the receiver and offer resistance to the back flow of oil or liquid into the compressor. This view indicating the flow of gas through this port to the receiver.

Fig. 5 is a similar view illustrating the 65 back flow of oil.

Fig. 6 is a view indicating a modified construction.

Fig. 7, a view illustrating still another 70 modification.

Figs. 8 and 9 are views illustrating modified forms of delivery ports.

Fig. 10 is a view illustrating still another 75 modified construction of delivery port.

Figs. 11 and 12 showing respectively the flow of gas and back flow of oil in the devices shown in Fig. 10.

Fig. 13 illustrates another form of rotary pump provided with my improvement, the view being taken on the line 13—13 of Fig. 14.

Fig. 14 is a front view of the pump shown in Fig. 13 partly in section on the line 14—14 of Fig. 13, and

Fig. 15 is an enlarged view showing the 85 construction of delivery port indicated in Fig. 13.

A and A', Fig. 2, indicate the cylinder of twin pumps formed in the same casting, A² and A³ being the face plates. B indicates 90 the cylindrical periphery of the pump chamber interrupted at point indicated at B', B², to give clearance to the piston extension. C is the bearing for the swivel block shown in Figs. 1 and 2. D is the admission chamber, E the delivery port of the compressor which in accordance with my invention is made restricted and of such a form as to pass the compressed gases readily and at high speed while offering resistance to the 95 back flow of oil. As shown in Figs. 1 and 3 and the enlarged views, Figs. 4 and 5, the port passage has inserted in it the cylindrical plug indicated at K in which is formed a tapered slot indicated at K', the slot tapering toward the receiving chamber of the compressor. As shown in Fig. 6 the delivery port is forked and has two slotted plugs K, K, located in the two branches of the port while, as shown in Fig. 7, two 100 slotted plugs K are inserted in the port in tandem. In the construction shown in Fig.

8 the plug E has formed in it three successive tapered slots arranged in tandem as indicated at K¹, K². As shown in Fig. 9 the plug K in addition to the tapered slot K' is 5 formed with slots indicated at K³, K⁴, which communicate through ports f, f, with the liquid chamber of the receiver. As shown in Fig. 10 the restrictions in the delivery port are formed through a segmental plate 10 L having formed through it more or less numerous and tapered circular passages indicated at L'.

F in Fig. 1 indicates the delivery chamber of the compressor which is formed so as 15 to include at its base a liquid containing chamber F' of such form and dimensions as to hold a body of liquid generally oil above the delivery port and in sufficient quantity to insure that the port shall be 20 covered by the liquid during the periods between the delivery of compressed gas. G indicates the driving shaft of the compressor to which are secured eccentrics indicated at G'. On these eccentrics are the eccentric 25 ring pistons H from which extend the slides indicated at I which, as shown in Figs. 1 and 2, have admission passages I' formed through them opening into the cylinder and port I² so spaced and proportioned that the 30 port will be closed by the face of the swivel block indicated at J at the top of the stroke of the piston.

In the construction shown in Figs. 13 and 14 I have illustrated a form of rotary compressor which is, generally speaking, equivalent for the form shown in Figs. 1 and 2. In place of having a slide extension on the eccentric ring piston sliding in a swivel block the piston is provided with an extension indicated at i which is articulated at N to a 40 lever arm M' pivoted at M in the center of a segmental bearing indicated at c the lever carrying the slide or slides working in this bearing, such a slide being indicated at O 45 and also, either separate from or as a part of this slide, an admission valve indicated at P working with an admission port Q formed in the bearing c and in connection with the admission chamber d. The delivery ports here shown as two in number are indicated at e, e, and the restrictions are formed by two segments indicated at L, L, and generally similar to those shown in Figs. 10, 11 and 12 except that they are here shown 50 as held in position by bolts indicated at r screwing into the inner portion of the casing while in Fig. 10 they are held in position by bolts R screwing through the outer portion of the casing.

60 In operation the gas to be compressed together with a considerable quantity of oil enters the compressor through the admission port until the compression chamber is fully charged at which point the admission port 65 is closed. The construction shown in Figs. 1

and 2 by the passage of the port I² upward beyond the edge of the swivel block J and in the construction shown in Fig. 13 by the passage of the slide valve P over the port Q after the piston has passed the gas between 70 the points B' and B² and comes in contact with the left hand side of the cylinder surface at B'. The admission valve is again opened to admit fresh charge of gas for compression. As soon as the pressure in the 75 compressor exceeds that in the receiver the compressed gas is delivered through the restricted port E passing for the most part with great velocity through the restricted ports, the velocity, however, diminishing as 80 the plunger approaches the port so that at the end of the compression cycle when probably none or but little gas remains in the compression cylinder the oil is forced through the delivery port at moderate speed. 85 The oil passing through the delivery port keeps the oil and liquid holding chamber F' substantially full of oil so that as soon as the piston has passed the delivery port this oil 90 will begin to flow back through the delivery port but owing to the restricted nature of the port and the non-compressible quality of the liquid the backward flow will be gradual and will not have time to acquire much 95 velocity before the pressure in the compressor will again exceed that in the receiver and the flow is reversed as already described.

In the specific form of compressor shown in Figs. 1 and 13 I have illustrated novel features of construction which are described 100 and claimed in my co-pending applications filed September 25, 1920, and October 6, 1920, Serial Nos. 412,822 and 415,128, and are therefore not specifically claimed in this 105 application except in so far as they form combinations with my novel construction of delivery ports.

Having now described my invention, what I claim as new and desire to secure by Letter Patent, is:

1. In combination with a compressor a delivery chamber, a liquid retaining chamber in said delivery chamber and one or more restricted valveless delivery ports opening from the compressor cylinder into 115 said liquid retaining chamber said ports being so proportioned that while they will permit the compressed gas to pass through them into the receiver at high speed they will offer high resistance to a back flow 120 of liquid from the liquid containing chamber.

2. In combination with a compressor a delivery chamber, a liquid retaining chamber in said delivery chamber said liquid chamber having such capacity as to retain above the delivery ports opening into it, a body of liquid greater in quantity than will flow backward through the delivery ports during the interval between delivery flows there- 125 130

through and one or more restricted valveless delivery ports opening from the compressor cylinder into said liquid retaining chambers said ports being of such formation that 5 while they will permit the compressed gas to pass through them at high speed they will offer high resistance to a back flow of liquid from the liquid containing chamber.

3. In combination with a rotary compres-
10 sor a delivery chamber, a liquid retaining chamber in said delivery chamber and one or more restricted valveless delivery ports opening into the liquid retaining chamber said ports being so proportioned
15 that while they will permit the compressed gas to pass through them at high speed they will offer high resistance to a back flow of liquid from the receiving chamber.

4. In combination with a rotary compressor having a rotating eccentric ring piston provided with an extension serving as a partition between the admission and delivery ports, a receiving chamber, a liquid retaining chamber in said receiving chamber and one or more restricted valveless delivery ports opening into the liquid retaining chamber said ports being so proportioned that while they will permit the compressed gas to pass through them at high speed they will offer high resistance to 20 a back flow of liquid from the receiving chamber, an admission port leading into the compressor and means acting to close said admission port during the period when the piston is out of contact with its cylinder.

GUSTAV B. PETSCHE.
